UNITED STATES PATENT OFFICE.

JOHN MASSEY, OF BUFFALO, NEW YORK.

MACHINE FOR HUSKING CORN.

Specification of Letters Patent No. 16,740, dated March 3, 1857.

To all whom it may concern:

Be it known that I, JOHN MASSEY, of the city of Buffalo, in the county of Erie and State of New York, have invented certain 5 new and useful Improvements in Machines for Husking Corn; and I do hereby declare that the following is a full and exact description thereof, reference being had to the accompanying drawings and the letters of 10 reference marked thereon.

Figure I, is an isometrical perspective of the machine; A, circular cutter plate; e, e, e, cutter teeth; B, revolving tubular bur; C, sliding table, upon which the ears of corn 15 are fed to the cutters; D, driving shaft for cutters; E, pulley to shaft n, n; G, multiplying pulley; H multiplying pulley; K, pulley on cutter shaft D; L, pulley on same shaft with the tubular bur B; M, M, M, 20 main frame; I, pulley, connecting by band to pulley L.

Fig. II, represents a top plan view of my machine. Letters of the same name refer to like parts, as in Fig. I.

Fig. III, represents a circular cover, which sets over the cutter when in use, in order to 25 protect the operator from accident. This cover has an opening at P, sufficient to allow the cutter to act upon the stalk and 30 husks, as the ears of corn are fed to the cutter on the sliding table C.

Fig. IV, represents a table which sets over the cover and over the shafts n, and D. Upon this table the corn is put before it is 35 husked, so as to be within the convenient reach of the operator.

The nature of my invention consists in the construction and use of a tapering, tubular revolving bur: for the purpose of 40 removing the husks from the ears of corn, after the husks and stalk have been severed by the cutter. I also employ a rotary bevel edged cutter for the purpose of severing the husks and stalk from the cob.

To enable others skilled in the art to make 45 and use my invention I will proceed to describe its construction and operation.

The drawings are made on a scale of about one inch and an half to the foot. The main 50 frame M, M, M, which supports the moving machinery is made of wood in a common workmanlike manner. I make my tapering tubular bur B, of sheet iron. It should be about five inches in length, and about three 55 inches in diameter at its mouth, and taper

to one inch in diameter at its connection, with its driving shaft. Small holes are punched through, so as to leave a bur on the inside. It is connected or fastened onto the end of the same shaft upon which is the 60 pulley L. It projects from the end of its shaft, so as to revolve outside of the frame as represented at B, in the drawings Fig. I. It is made to revolve rapidly, by means of a band, from the pulley I, to the pulley L. 65 This bur is sufficiently broad at its mouth to admit the largest sized ear of corn, and also tapering to one inch in diameter at its smallest end it will catch, and strip off, the husks from any sized ear of corn. The ear of corn 70 being required to enter only far enough for the bur to catch the husks and strip them from the corn.

In operating the machine the ears of corn are brought together, and placed upon the 75 table, which sits upon the main frame, over the shafts n, and D, (which table is represented in Fig. IV) so as to be within reach of the operator. The operator now takes the corn, ear by ear and with his hand holds them 80 upon the sliding table C, so as to bring the butt of the cob in range with the cutter. The sliding table is now moved toward the cutter, so that the husks and stalk will be severed, close to the corn. When this is 85 done, and before the corn has passed from the hand of the operator, the tip of the ear of corn is thrust into the revolving tubular bur B, and the husks are thereby loosened and removed from the corn. In this manner 90 the husks can be removed from the corn with great rapidity.

My revolving cutter (represented at A, e, e, e, Fig. I,) is about sixteen inches in diameter. It is made of the best quality of 95 sheet steel. The teeth e e e are beveled on one side only, and brought to an edge—the bevel extending onto the cutter plate about three inches. This gives a smooth cutting edge, like a carpenter's chisel. An advantage is gained by this form of cutter over a saw, or any cutter which cuts away a chip, for the reason that the corn stalk is of such a stringy, fibrous character that it is liable to clog the cutter, unless the cut is smooth 100 and sharp and upon an angle.

I am not aware that cutters of this description have ever before been employed for this purpose.

The drawings represent the machine, to be 110

propelled by hand power from the pulley E. In case steam or horse power should be applied such power would be applied by a band running on pulley K. In such case, 5 the pulleys G, and H, and the crank pulley E, would be dispensed with.

All parts of the machine may be constructed by an ordinary workman, skilled in the art to which each part appertains.

10 I do not wish to limit myself to the particular proportions herein set forth but desire to include only such forms and propor-

tions as substantially embrace the principle of my invention.

I claim—

15 The tapering tubular bur B for the purpose of removing the husks from the corn, when arranged and operating substantially as herein set forth.

JOHN MASSEY.
